UNITED STATES PATENT OFFICE.

LEE S. CHADWICK, OF EAST CLEVELAND, OHIO, ASSIGNOR TO THE CLEVELAND
FOUNDRY COMPANY, OF CLEVELAND, OHIO, A CORPORATION OF OHIO.

LIQUID-DISPENSING APPARATUS.

1,209,811.

Specification of Letters Patent. Patented Dec. 26, 1916.

Application filed September 27, 1916. Serial No. 122,402.

To all whom it may concern:

Be it known that I, LEE S. CHADWICK, a citizen of the United States, residing at East Cleveland, in the county of Cuyahoga and State of Ohio, have invented a certain new and useful Improvement in Liquid-Dispensing Apparatus, of which the following is a full, clear, and exact description, reference being had to the accompanying drawings.

This invention relates to improvements in liquid dispensing apparatus, and particularly to such as is suitable for incorporation in liquid fuel stoves.

The object of the invention is to provide a liquid dispensing apparatus involving a distributing receptacle, a carrier pivotally supported to swing from a position at one side of to an inverted position over the distributing receptacle, and a dispensing receptacle having a pivoted bail and which may be placed within the carrier when the same is in the first position and swung therewith to inverted position retaining means being provided wherewith the bail of the dispensing receptacle engages during the inversion of the carrier to hold the bail out of the way, and in a position where it will be free from the liability of liquid accumulating thereon.

From the foregoing it will be seen that the invention is peculiarly adapted to liquid fuel stoves, for in such cases it is an obvious advantage to keep the handling means or bails of the dispensing receptacle free from oil, thus allowing them to be freely handled by the user of the stove while the user is engaged in cooking or some such work without liability of soiling the hands.

Further objects are to provide an arrangement whereby the dispensing receptacle is required to be placed in proper position within the carrier so that its bail will drop in operative relation to the keeper that is attached to the carrier; and to so construct and arrange the parts of the apparatus that such correct placement of the dispensing receptacle is performed instinctively and in a most natural manner.

The foregoing objects are attained in a construction illustrated in the accompanying drawing wherein—

Figure 1 represents a partial front elevation, and Fig. 2 a side elevation of liquid fuel stove embodying my invention; Fig.

3 is an enlarged fragmentary end elevation of the stove with the carrier occupying a position alongside the distributing receptacle and supporting a dispensing receptacle, parts being broken away to clearly reveal certain structural details; and Fig. 4 is a similar view with the carrier and dispensing receptacle inverted above the distributing receptacle.

The stove wherein I have shown my invention incorporated comprises a base 1, supported by legs 2, and above which there is sustained, by end panels 3; a top 4. A liquid fuel supply pipe extends longitudinally of the stove and is shown as passing through the right hand end panel 3. Between the end panels, burners 6 are communicatively connected to the supply pipe, and each burner is provided with the usual drum 7. (While I have shown but one end of the stove in Fig. 1, it will be understood that the frame of the stove is substantially symmetrical and that the end panel shown is duplicated at the opposite end).

Beyond the right hand end panel 3, an open top distributing receptacle 10 is communicatively connected to and partially supported by the pipe 5, the same being further supported by a bracket 11 which is attached to the end panel and extends outward therefrom to where it has connection with the distributing receptacle adjacent its top. A drain extension 12 projects forwardly from the top of the distributing receptacle, and in its side walls 13 is supported a pintle 14 to which is hinged the carrier designated 15.

The carrier is composed of a semi-cylindrical wall to which the reference numeral 15 is applied, and at its end adjacent the drain extension 12, has attached to it a plate 18 that has its outer end turned about the pintle 14 to form a hinge connection with the distributing receptacle. An end member 20 is secured to the free end of the cylindrical wall 15 and the same comprises a circular end wall 21 that is surrounded by a comparatively shallow flange 22. Diagonally across from its hinge, the carrier is provided with a finger hold 25 that is preferably formed of a loop of metal having an extension which is spaced from the wall 22 of the member 20 and constitutes a keeper 26 for the bail of the dispensing receptacle, as will be presently explained, the space be-

tween the keeper and wall of the member 20 opening toward the free end of the carrier.

The dispensing receptacle may consist of a bottle 30 the upper end of the body portion 6 of which is surrounded by a band 31 for the purpose of producing a shoulder 32 which is adapted to enter and be supported by a ledge 33 of the carrier, the ledge being preferably formed by turning inward the end of the 16 wall 15 of the carrier adjacent the hinge plate 18. The mouth of the dispensing receptacle is provided with a valve 35. A U-shaped bail 36 has its ends pivotally connected to the band 31, at 37, and the inwardly turned end portions of the bail are adapted to engage the adjacent edge portions of the wall 15 when the dispensing receptacle is placed within the carrier, thereby to position the dispensing receptacle so that 20 the central portion of its bail will have to fall directly beneath the open side of the space between the keeper 26 and the wall of the member 20.

Let it be assumed that the dispensing receptacle has been so placed within the carrier, as illustrated in Fig. 3. The carrier may now be swung to inverted position by grasping the finger hold 25, and in so doing, the dispensing receptacle will gravitate toward the hinged or pivoted end of the carrier, the central portion of the bail now engaging the keeper 26 and being retained thereby in elevated position, and the shoulder 32 of the dispensing receptacle resting upon the ledge 33 of the carrier. In inverted position, as shown in Fig. 4, the stem of the valve 35 engages the bottom of the distributing receptacle, unseating or opening the valve and allowing sufficient of the 35 contents of the dispensing receptacle to flow into the distributing receptacle as will rise therein and form a seal for the mouth of the dispensing receptacle, in a common and well known manner.

45 It may be explained that the proper relation is established and maintained between the carrier and distributing receptacle when the former is inverted above the latter by steps 49 which extend from the end of the 50 wall 15 of the carrier and engage the drain extension 12 of the distributing receptacle; and that the carrier is maintained in proper 55 position when swung downward and away from the distributing receptacle by the engagement of a bracket 41, secured to the member 20 of the carrier, with a stop 42, which projects from the end panel of the stove.

56 Having thus described my invention, what I claim is:

1. In a liquid dispensing apparatus, the combination of a distributing receptacle, a carrier pivotally supported to swing from a position at one side of to an inverted position over the distributing receptacle, a dis-

70 pensing receptacle adapted to be placed in the carrier when the latter is in the first position and swung therewith to inverted position, the dispensing receptacle having a bail and being capable of a downward movement with respect to the carrier as they assume inverted position, the carrier having a keeper wherewith the bail of the dispensing receptacle engages during the aforesaid downward movement of the dispensing receptacle. 75

2. In a liquid dispensing apparatus, the combination of a distributing receptacle, a carrier pivotally supported to swing from a position at one side of, to an inverted position over the distributing receptacle, a dispensing receptacle adapted to be placed in the carrier when the latter is in the first position and to be swung therewith to inverted position, the dispensing receptacle being capable of a downward movement with respect to the carrier as they assume inverted position, the dispensing receptacle having a bail and the carrier a keeper wherewith the bail engages during the aforesaid downward movement of the dispensing receptacle, the dispensing receptacle and carrier having portions which cooperate to locate the bail in proper relation to the keeper. 90

3. In a liquid dispensing apparatus, the combination of a distributing receptacle, a carrier pivoted to said distributing receptacle and adapted to swing from a position at one side of, to an inverted position over the distributing receptacle, a dispensing receptacle adapted to be placed in the carrier and swung therewith to inverted position, means for properly locating the dispensing receptacle within the carrier, the dispensing receptacle having a pivoted bail, and the carrier having a keeper and an operating handle that are located at a point diagonally opposite its pivoted portion, the bail assuming a position adjacent said keeper when the dispensing receptacle is placed within the carrier and adapted to engage the same when the carrier is swung to inverted position. 100

4. In a liquid dispensing apparatus, the combination of a distributing receptacle, a carrier pivotally supported to swing from a position at one side of, to an inverted position over the distributing receptacle, a dispensing receptacle adapted to be placed in the carrier and swung therewith to inverted position, the dispensing receptacle having a bail and the carrier a keeper wherewith the bail automatically engages during the inversion of the carrier. 115

5. In a liquid dispensing apparatus, the combination of a distributing receptacle, a carrier pivotally supported to swing from a position at one side of, to an inverted position over the distributing receptacle, a dispensing receptacle adapted to be placed 125

1,209,811

3

in the carrier and swung therewith to inverted position, the dispensing receptacle having a bail and the carrier a keeper therefor.

5 6. In a liquid dispensing apparatus, the combination of a distributing receptacle, a carrier pivotally supported to swing from a position at one side of, to an inverted position over the distributing receptacle, a dispensing receptacle adapted to be placed in the carrier and swung therewith to inverted position, the dispensing receptacle having a handling device and the carrier a keeper, the former being adapted to drop 10 into operative relation with the latter when the dispensing receptacle is placed in the carrier and interlock therewith when the carrier is inverted.

20 7. In a liquid dispensing apparatus, the combination of a distributing receptacle, a carrier pivotally supported to swing from a position at one side of, to an inverted position over the distributing receptacle, a dispensing receptacle having a handling device and adapted to be placed in the carrier when the latter is in the first position and swung therewith to inverted position, and a keeper wherewith the handling device of the dispensing receptacle is adapted to be 25 engaged and to be retained thereby in a given position.

30 8. In a liquid dispensing apparatus, the combination of a distributing receptacle, a carrier pivotally supported to swing from a position at one side of to an inverted position over the distributing receptacle, a dispensing receptacle adapted to be placed in the carrier and swung therewith to inverted position, the dispensing receptacle 35 having a bail and the carrier a keeper therefor wherewith the bail automatically engages during the inversion of the carrier, and means for locating the dispensing receptacle within the carrier so as to present 40 its bail in proper relation to the keeper.

45 9. In a liquid dispensing apparatus, the combination of a distributing receptacle, a carrier supported so as to swing from a position at one side of to an inverted position over the distributing receptacle, a dispensing receptacle adapted to be placed in and swung with the carrier into operative position with respect to the distributing receptacle, the dispensing receptacle being 50 capable of sliding with respect to the carrier during the inversion thereof, the dispensing receptacle having a bail and the carrier a keeper into engagement with which the bail moves during the sliding of the dispensing receptacle, and means for locating the dispensing receptacle to bring 55 its bail in proper relation to the keeper.

60 10. In a liquid dispensing apparatus, the combination of a distributing receptacle, a carrier supported so as to swing from a

position at one side of to an inverted position over the distributing receptacle, a dispensing receptacle adapted to be placed in and swung with the carrier into operative position with respect to the distributing receptacle, the dispensing receptacle being 70 capable of sliding with respect to the carrier during the inversion thereof, the dispensing receptacle having a bail, a keeper into engagement with which the bail moves 75 during the sliding of the dispensing receptacle, and means for locating the dispensing receptacle to bring its bail in proper relation to the keeper.

80 11. In a liquid dispensing apparatus, the combination of a distributing receptacle, a carrier pivotally supported to swing from a position at one side of, to an inverted position over the distributing receptacle, a dispensing receptacle adapted to be placed 85 in the carrier and swung therewith to inverted position, the dispensing receptacle having a handling device and the carrier a keeper, the former being adapted to drop into operative relation with the latter when the dispensing receptacle is placed in the carrier and interlock therewith when the carrier is inverted.

88 12. In a liquid dispensing apparatus, the combination of a distributing receptacle, a carrier pivotally supported to swing from a position at one side of, to an inverted position over the distributing receptacle, a dispensing receptacle having a handling device and adapted to be placed in the carrier when 100 the latter is in the first position and swung therewith to inverted position, and a keeper wherewith the handling device of the dispensing receptacle is adapted to be engaged and to be retained thereby in a given position.

105 13. In a liquid dispensing apparatus, the combination of a distributing receptacle, a carrier movable from inoperative to operative position with respect thereto, a dispensing receptacle adapted to be placed in and to be moved with the carrier, the dispensing receptacle having a handling device and the carrier a keeper into engagement with which said device is moved when the carrier is moved to operative position, and means for locating the dispensing receptacle with its handling device in proper relation to the keeper.

110 14. In a liquid dispensing apparatus, the combination of a distributing receptacle, a carrier movable from inoperative to operative position with respect thereto, a dispensing receptacle adapted to be placed in and to be moved with the carrier, said dispensing receptacle having a handling device, and a keeper for said device into engagement with which the device is moved when the carrier is moved to operative position.

120
125
130

15. In a liquid dispensing apparatus, the combination of a distributing receptacle, a dispensing receptacle having a handling device, an element for supporting the dispensing receptacle in operative relation to the distributing receptacle, and a keeper for the handling device of the dispensing receptacle is presented in operative relation to the distributing receptacle.

16. In a liquid dispensing apparatus, the combination of a distributing receptacle, a dispensing receptacle having a handling device, an element for supporting the dispensing receptacle in operative relation to the distributing receptacle having a handling device, an element for supporting the dispensing receptacle in operative relation to the distributing receptacle.

the distributing receptacle, and a keeper for the handling device of the dispensing receptacle into engagement with which the said device automatically moves when the dispensing receptacle is presented in operative relation to the distributing receptacle, and means for locating the dispensing receptacle with respect to the supporting element so that the handling device is presented in proper relation to the keeper.

In testimony whereof, I hereunto affix my signature in the presence of two witnesses.

LEE S. CHADWICK.
